UNITED STATES PATENT OFFICE.

JOHN RICHARD CONRAD, OF LONG PINE, NEBRASKA.

OVEN-DOOR.

SPECIFICATION forming part of Letters Patent No. 374,889, dated December 13, 1887.

Application filed March 25, 1887. Serial No. 232,438. (No model.)

To all whom it may concern:

Be it known that I, JOHN RICHARD CONRAD, of Long Pine, in the county of Brown and State of Nebraska, have invented a new and 5 useful Improvement in Oven-Doors, of which the following is a specification.

The object of my invention is to provide means for accurately telling the heat or temperature of a stove-oven, and for inspecting 10 the contents of the same without opening the door.

The invention consists in the novel arrangement and combination of parts, all as herein-after fully described, and pointed out in the 15 claims.

Figure 1 is a side elevation of a cooking-stove having my improvement applied. Fig. 2 is an inside view of the door. Fig. 3 is a section of the same on the line *x x*. Fig. 4 is 20 a perspective view of the securing-plate.

Similar letters of reference indicate corresponding parts in all the figures.

Referring to the drawings by letter, A represents an ordinary cooking-stove, and B the 25 oven-door. In the door B, I form an opening, *b*, preferably T-shaped, as shown, and over this opening I secure the isinglass or other transparent material, C, by means of the securing-plate D. The upper portion of the plate

30 D fits around the upper part of the opening *b* in the door, and its lower or stem portion, *d*, is formed with a semicircular depression or groove, *d'*, for the reception of the thermometer E. The groove *d'* of the plate D extends 35 to the lower end of stem, and its middle portion is slotted, as shown, to permit a free circulation of the heat around the thermometer. This circulation of the heat may be increased by corrugating the stem transversely, the cor- 40 rugations extending from the sides of the stem to the groove *d'*. The lower portion of the isinglass or transparent material in front of the thermometer will be graduated as shown, the letters thereon representing the terms com-

monly used by cooks, viz: "Warm," "Slow," "Moderate," "Quick," "Hot," and "Burn- 45 ing." The thermometer will be secured in the groove of the plate D by means of a fine wire, or by any other suitable means, and the 50 plate is secured to the door by means of bolts *c*.

By means of my improvement the contents of the oven can be readily inspected without opening the door, thereby saving time and trouble, to say nothing of the loss of heat incident to the repeated opening of the door. 55 By my improvement, also, provision is made for accurately telling the heat or temperature of the oven, thereby doing away with guess-work and reducing baking to a science. If desired, a similar or other shaped opening covered with isinglass or other transparent material may be made in the other door, in order to afford more light.

Instead of graduating the isinglass or other transparent material, the graduation may be 65 formed on the outside of the oven-door at one side of the slot; or the outside of the door may be made to receive a fancy nickeled design with a T-shaped opening, as in door, and upon this design the graduations will be formed. 70

Having thus described my invention, what I claim, and desire to secure by Letters Patent, is—

1. As an improved article of manufacture, the thermometer and pane-securing plate D 75 for oven-doors, having an elongated opening in its upper part and provided with a groove, *d*, having a slot, *d'*, in its lower or stem portion, as specified.

2. The combination, with an oven-door having a T-shaped opening, of graduated transparent material over the said opening, a securing-plate having an elongated opening in its upper part and a socket in its stem portion, and a thermometer in said socket, substan- 85 tially as herein shown and described.

3. The combination, with an oven-door provided with a T-shaped opening, of the plate D, having an elongated opening in its upper part and provided with the slotted groove *d d'* 90 in its stem portion, the thermometer E in the said groove, and the graduated transparent material between the plate and door, substan- tially as herein shown and described.

JOHN RICHARD CONRAD.
